CLOTHES HANGER

Carl E. Gingher, 304-328 Depot St., Scranton, Pa.

Filed Apr. 27, 1964, Ser. No. 79,708

Term of patent 14 years

(Cl. D80—8)

FIG.1

The characteristic feature of my design resides in the specific clothes clamping unit in association with the clothes hanger as shown.

I claim:

The ornamental design for a clothes hanger, as shown and described.
